UNITED STATES PATENT OFFICE.

JAMES F. McBIRNEY, OF HARTFORD, CONNECTICUT, ASSIGNOR TO ROYAL TYPEWRITER COMPANY, OF NEW YORK, N. Y., A CORPORATION OF NEW JERSEY.

TYPE-WRITING MACHINE.

1,010,290.

Specification of Letters Patent. Patented Nov. 28, 1911.

Application filed July 2, 1908. Serial No. 441,540.

To all whom it may concern:

Be it known that I, JAMES F. McBIRNEY, a citizen of the United States of America, residing in Hartford, county of Hartford, 5 and State of Connecticut, have invented certain Improvements in Type-Writing Machines, of which the following is a specification.

This invention relates to a new organization 10 comprising means for provision of any desired number of so-called "silent keys" in the key-board, either to the right or left of the longitudinal center of the machine, for printing accents and for other purposes 15 where an impression is made without feed of the carriage.

In the accompanying drawing: Figure 1 20 is an elevation of the right hand side of a typewriting machine, with the side plate broken away and partly in section, shewing so much of a machine as is desirable to illustrate this invention: Fig. 2, a detail front elevation showing rocking devices to which are to be connected links that are operated 25 upon depression of silent-key finger-pieces: Fig. 3, an end elevation of Fig. 2: Fig. 4, a detail side elevation: and Fig. 5, a perspective view showing a modification of the construction.

30 This invention is shown applied to the "Standard" typewriting machine made by the Royal Typewriter Company and now well known in the market.

1 indicates the platen and 2 is the shift 35 rail of the carriage in which the platen is mounted.

3 is the ribbon vibrator jointed at 4 to the forwardly extending horizontal arm 5 of a bell crank lever whose depending arm 6 is 40 connected with a link 7 bifurcated or slotted at its rear end 8 to embrace a pin 9 on the suspended universal bar 10 carried in the lower ends of links 11 whose upper ends are pivoted on-shaft 12 mounted in the frame.

45 These links are cross connected above the universal bar by a tie rod 11'. A plate having a forward projection 13 is secured to the tie rod and universal bar and when the latter is drawn forward, contacts with the end 14 of the escapement rocker 15 pivoted at 16. When therefore the universal 50 bar is drawn forward, the pin 9, working against the end wall of the slot in the rear end 8 of link 7, carries that link forward to

projection 13, striking the escapement rocker 15 operates the escapement.

17 is the type bar segment and 18 indicates a type bar pivoted therein. The bar 18 is one of the ordinary letter bars operated by a link 19 extending forward to the end of a push pin 20 to which also is connected the rear end of a link 21 rocking about a fixed axis or anchor point 22. On the link 19 in front of the pivot of its type bar is a 60 projection 10' to which is jointed the front end of a link 10² whose rear end is hooked over the universal bar 10. A coiled spring serving to hold the parts in normal position has one end connected to projection 10' and 65 the other to a transverse horizontal plate 25 mounted at the back of the machine. All the printing keys that operate the universal bar are similarly arranged. When such a key is depressed the type bar will be pulled 70 to the printing point by link 19 and the universal bar be drawn forward by link 10² to actuate both the ribbon vibrator and escapement.

The construction thus far described is substantially that of the Royal Typewriter Company's "Standard" machine. 80

Provision for a plurality of so-called silent keys is made as follows: A rock shaft 23 is mounted to turn in bearings 24 on the horizontal plate 25 having at each end slotted upturned parts 26 by which the plate may be bolted as at 27 to the rear part of the frame of the machine. Preferably, this rock shaft is mounted in rear of the universal bar, and 85 is parallel therewith. Centrally secured to the rock shaft is a projection or wiper arm 28 adapted to strike the rear end of the link 7. As shown it engages a shoulder 8' on the link. A spring 29 normally tends to rock 95 the shaft 23, as viewed in Fig. 1, in the direction in which turn the hands of a watch. On each side of the wiper 28, a pair of arms 49 is secured to the rock shaft and extending between the upper ends of such arms is a 100 rod 30. 31 is the finger piece of a silent key, shown in this instance as a push pin 32 having connected to its lower end a link 21' rocking at the front about a fixed point 22', and also a link 19' connected at its rear end 105 to the heel of a type bar 33. Attached to the link 19' is a downwardly extending piece 34 to which is jointed a link 36 the hooked rear end of which embraces the rear

pin 31, 32, is depressed, the type bar 33 is thrown to the printing point and the link 36 draws forward the rod 30 rocking the shaft and carrying forward the wiper 28 which, striking the rear end of the ribbon vibrator link 7, 8, operates the ribbon vibrator. The escapement, however, remains inoperative since no movement is imparted to the universal bar. The rods 30 disposed 10 respectively on opposite sides of the center of the machine may be of such length as is desired. The arms 49 that carry them are secured to the rock shaft 23 adjustably by means of the set screws 38. There is or may 15 be provided therefore a means of connection for the links 36, of a plurality of silent keys located at any point in the key board either to the right or left of the center. The construction is such as to afford the greatest 20 number of silent keys that could possibly be employed under any circumstances.

Figs. 4 and 5 show a slight, and indeed an obvious modification of the construction. The rods 30 are omitted and the rock shaft 23 turns in end bearings 23'. There is adjustably secured upon the rock shaft by means of a set screw 39 a plate 40 apertured or slotted at 41 for the reception of the rear hooked end of a silent key link 36. Any desired number of such plates 40 located at any point in the length of the rock shaft may be used. Some one of the plates 40 may have applied to it the spring 29 indicated in Figs. 2 and 4 one end of the spring bearing 35 against the frame of the machine and the other engaging an aperture 42 in the plate 40 or the arm 49 as the case may be. Secured centrally upon the rock shaft is an arm or wiper 28 shown, in this instance, 40 as long enough to contact with the rear end of the lower bifurcation at the end of link 7. Of course, the silent key or push pin 31, 32 should have a spring to return all parts to normal position. This spring may be arranged or located in any way desired. The drawing indicates the employment of a spring 43 connected at its rear or lower end to the push pin and at its front or upper end to the lug 44 constituting the anchor 45 point of the link 21'. The universal bar 50 may be retracted by the spring 50 applied to the ribbon vibrator bell-crank.

I claim:

1. The combination with the platen, type bars, finger pieces, operative connections between the finger pieces and type bars comprising type bar operating links that pull the type bars to the printing point, a universal bar, link connections from the major number of the last named links to the universal bar, a ribbon vibrator and escapement devices both actuated by the universal bar, a transversely disposed rocking member provided with means for actuating the ribbon vibrator without actuation of the escape-

ment and also with means for connection of a plurality of links extending from some of the type bar operating links.

2. The combination with the platen, type bars, finger pieces, operative connections between the finger pieces and type bars comprising type bar operating links that pull the type bars to the printing point, a suspended universal bar, link connections from the major number of the last named links to the universal bar, a ribbon vibrator and escapement devices both actuated by the universal bar, a transversely disposed rocking member provided with means for actuating the ribbon vibrator without actuation of the escapement and also with means for connection of a plurality of links extending from some of the type bar operating links. 75 80

3. The combination with the platen, type bars, universal bar, escapement devices and ribbon vibrator devices, of an operating push pin for each type bar, two links connected to each push pin; one having its front end mounted to rock about a fixed point and the other having its rear end connected to its type-bar, a draw link for each of the major number of type-bars actuated when its type bar is actuated and engaging at its rear end the universal bar, a transversely arranged member extending on both sides of the center of the machine, movable back and forth and having means for actuating the ribbon vibrator without actuation of the escapement, one or more draw links actuated when some other of the type bars are actuated and engaging at their rear ends said movable member. 85 90 95 100

4. The combination of a platen, type bars, finger pieces, type bar operating links actuated by the finger pieces to pull the type bars to the printing point, a universal bar, link connections that correspond with the major number of finger pieces and are applied to the universal bar and are operated by their respective finger pieces, a ribbon vibrator and escapement devices actuated by the universal bar, a transversely disposed movable member provided with means for actuating the ribbon vibrator without actuation of the escapement and actuating links 105 110 115 that correspond with and are operated by some of the finger pieces and are applied to said member.

5. The combination of a platen, type bars, finger pieces, type bar operating links actuated by the finger pieces to pull the type bars to the printing point, a universal bar, link connections that correspond with the major number of finger pieces and are applied to the universal bar and are operated by their respective finger pieces, a ribbon vibrator and escapement devices actuated by the universal bar, a transversely disposed rocking member provided with means for actuating the ribbon vibrator without actu- 120 125 130

- ation of the escapement and horizontally disposed actuating links that correspond with and are actuated by some of the finger pieces and are applied to said member.
- 5 6. In a visible typewriting machine, the combination of a platen, a ribbon vibrator, escapement devices, pivoted type bars, finger pieces corresponding with the type bars, type bar operating devices interposed be- 25
- 10 tween the finger pieces and their respective type bars, a universal bar, operative connec- 30
- 15 tions corresponding with the major number of the finger pieces and normally engaging the universal bar and operated to actuate it on depression of their finger pieces, means by which the universal bar actuates the ribbon vibrator and the escapement de- 35
- 20 vices, a transversely disposed movable silent key member, extending on both sides of the horizontal center of the machine, means by which said member actuates the ribbon vi- 40
- brator, and operative connections between a plurality of the finger pieces and said silent key member.
7. In a visible typewriting machine, the combination of a platen, a ribbon vibrator, escapement devices, pivoted type bars, finger 25
- pieces corresponding with the type bars, type bar operating devices interposed be- 30
- tween the finger pieces and their respective type bars, a universal bar, operative connec- 35
- tions corresponding with the major number of the finger pieces and normally engaging the universal bar and operated to actuate it on depression of their finger pieces, means by which the universal bar actuates the ribbon vibrator and the escapement de- 40
- VICES, a transversely disposed movable silent key member, extending on both sides of the horizontal center of the machine, means by which said member actuates the ribbon vi- 45
- brator, and operative connections between a plurality of the finger pieces and said silent key member.

In testimony whereof, I have hereunto
subscribed my name.
